ATTORNEY.

UNITED STATES PATENT OFFICE.

HENRY M. AUSTIN, OF BELLows FALLS, VERMONT.

ASH-SIFTER.

SPECIFICATION forming part of Letters Patent No. 699,134, dated May 6, 1902.

Application filed September 16, 1901. Serial No. 75,444. (No model.)

To all whom it may concern:

Be it known that I, HENRY M. AUSTIN, a citizen of the United States of America, residing and having post-office address at Bellows Falls, in the county of Windham and State of Vermont, have invented certain new and useful Improvements in Ash-Sifters, of which the following is a description, reference being had to the accompanying drawings, where—

10 Figure 1 is a perspective view showing the rear and other parts of an ash-sifter embodying said improvements. Fig. 2 is a perspective view showing the front and other parts of said ash-sifter. Fig. 3 is a view of what is 15 shown in Figs. 1 and 2 in central vertical section. Fig. 4 is a detail side view, on an enlarged scale, of the doors to the inlet-opening and of the parts which automatically operate the same. Fig. 5 is a view of the secondary 20 screen. Fig. 6 is a view of the primary screen.

The object of the improvement is the production of a device useful for sifting or screening burned coal, separating the coal and the cinders from the ashes in the operation. It 25 may also be used for any cognate purposes.

In the accompanying drawings the letter A denotes the main box or casing; B, a hinged lid; C, a vertical sliding door closing the outlet-opening; E, an inlet-opening; F and G, 30 two swing doors to the inlet-opening.

The letter H denotes the slanting primary screen, the letter I denotes the slanting shelf under the primary screen, and the letter K denotes the secondary screen, which leads to 35 and out of the outlet-opening D.

The letter L denotes a crank-arm practically rigid with the door F in the rotary movement of the two. The letter M denotes a similar crank-arm practically rigid with the door 40 G in the rotary movement of the two.

The letter N denotes a link from the arm L to the lever P. The letter O denotes a similar link from the arm M to the lever P. The lever P is pivoted to the inside of the casing 45 at about its center.

The letter W denotes a weight which operates to automatically close the two doors F and G through the medium of the chain, (running over the pulley S,) the lever P, the links N O, and the crank-arms L M.

When the unsifted stuff is dumped into the inlet-opening E, it falls upon the doors F and G, which open to permit the passage of the stuff and are then closed automatically by the weight W and the intermediates just mentioned. This automatic closing of the doors F and G prevents the dust incident to the screening process from escaping out of the casing A to the annoyance and hurt of the person using the device. The unsifted stuff falls 60 upon the primary slanting screen H. A good portion of the ash sifts through the same, while the unsifted part passes onto the secondary slanting screen K. At the same time the ash which has passed through the screen H 65 falls upon the slanting shelf I, which underlies the primary screen, and falls therefrom upon the secondary screen K, passing through the same into the space at the bottom of the casing. The unsifted stuff which falls upon the 70 secondary screen K from the primary screen H passes downward along that secondary screen. Practically all the remaining ash thereof sifts through the secondary screen into the open space in the lower part of the 75 casing. Finally, if the door C be open the coal and cinders pass out at the outlet D.

I claim as my improvement—

In combination, the casing having inlet-opening, the double-hinged doors to said inlet-opening, the single weight for automatically closing both doors, and the intermediate chain, lever, links and crank-arms, all substantially as described and for the purposes set forth.

HENRY M. AUSTIN.
